Communication dated Jan. 31, 2019, from Japanese Patent Office in counterpart application No. 2018-010137.

Primary Examiner — T Chase Nelson*Assistant Examiner* — Mary Claire Ramirez(74) *Attorney, Agent, or Firm* — Sughrue Mion, PLLC(57) **CLAIM**

The ornamental design for a digital camera, as shown and described.

DESCRIPTION

FIG. 1 is a front-left perspective view of a digital camera showing my new design;

FIG. 2 is a front-right perspective view thereof;

FIG. 3 is a rear-right perspective view thereof;

FIG. 4 is a rear-left perspective view thereof;

FIG. 5 is a front view thereof;

FIG. 6 is a rear view thereof;

FIG. 7 is a top plan view thereof;

FIG. 8 is a bottom plan view thereof;

FIG. 9 is a right side view thereof; and,

FIG. 10 is a left side view thereof.

The broken lines depict portions of the digital camera that form no part of the claimed design.
